ROTOR

Carl E. Tack, Chicago, Ill., assignor to American
Steel Foundries, Chicago, Ill., a corporation of
New Jersey

Application September 8, 1941, Serial No. 409,999

14 Claims. (Cl. 188—218)

My invention relates to brake equipment and particularly to a novel form of rotor designed to be associated with other braking means commonly called stators whose engagement with said rotor is commonly utilized as a means of stopping a wheel or other rotating member.

My novel rotor is particularly adapted for use with railway rolling stock and is so illustrated, although it will be understood that such a rotor may be utilized for any equivalent purpose for which it may be readily adapted.

In the present development of off-wheel brakes for railway rolling stock, it has been found necessary to develop a particularly rigid rotor capable of dissipating a tremendous amount of heat energy in order to afford stopping means for present day high speed trains.

The general object of my invention is to devise a rotor which will be eminently satisfactory for such a purpose and wherein the required strength as well as the heat dissipating qualities will be afforded and which at the same time will readily meet practical requirements of manufacture as well as necessary operating conditions.

A specific object of my invention is to devise such a rotor comprising a disc-like support which may readily be fastened to the hub of a wheel and serve as carrying means for a brake ring, said brake ring comprising a double blower in which the respective blowers are effective as in a circulating cooling means for braking surfaces at opposite sides of the ring.

A different object of my invention is to devise such a rotor as above described wherein the stresses resulting from compression of said rotor between engaging stators will be reduced to a minimum well within practical limits.

Yet another object of my invention is to form such a novel rotor structure wherein the parts will be so proportioned as to reduce to a minimum the weight of the rotor structure as a whole, while at the same time, so disposing the elements thereof as to meet the maximum stress conditions encountered in use and also permitting convenient manufacturing practice.

My invention also comprehends such an arrangement as that described wherein the central web or supporting disc of the rotor may be fixed on the wheel in such a manner as to prevent eccentricities thereof under normal operating conditions.

Yet another object of my invention is to devise a novel form of rotor such as above described wherein maximum radiating area will be afforded

for dissipation of the heat normally developed in use.

My invention also contemplates a novel rotor structure wherein the friction element comprises spaced integrally formed rings, certain of said rings affording a means of connection to the supporting disc or central web, while at the same time, serving as a means of dividing said friction ring into two blowers independently effective to cool the respective friction areas at opposite sides of said friction ring.

My invention also has as an object a construction of a novel rotor such as that last referred to wherein the ring connected to the central web or support disc may have a relatively short radial diameter as compared with the friction rings at opposite sides thereof so that the cooling medium drawn from opposite sides of the rotor may be mixed between the friction rings thereof to afford maximum turbulence and cooling effect.

Figure 1 is a side elevation of my novel form of rotor.

Figure 2 is an edge view taken from the left as seen in Figure 1 with a portion cut away along the radial planes indicated by the line 2—2 of Figure 1.

Figure 3 is a sectional view through a fragmentary portion of a wheel and axle assembly showing the manner of mounting my novel rotor thereon, said rotor being shown in section with the section taken substantially in the plane indicated by the line 3—3 of Figure 1.

Figure 4 shows an alternate manner of mounting my novel rotor on an associated wheel.

Figure 5 shows an alternate form of friction ring and blower which I may utilize in my novel form of rotor.

Figure 6 is a detailed view in side elevation of my novel form of central disc or rotor support member, and Figures 7 and 8 are sectional views therethrough, the view of Figure 7 being taken along the radial planes indicated by the lines 7—7 of Figure 6, and the view of Figure 8 along the radial plane indicated by the line 8—8 of Figure 6.

My novel rotor is shown in detail in Figures 1 and 2 and may be described as comprising a rotor support generally designated 2, said rotor support being of disc-like form including a hub portion 4 integrally formed with a bell-like member 6, the shape of which is best indicated in the sectional views of Figures 2 and 3 and the outer perimeter of which may be formed to a taper as indicated at 8 (Figure 3) for support of the rotor generally designated 10 which may be cast

therearound. Reference will be made hereafter in greater detail to the rotor support member 2. The rotor 10 is an integral casting comprising three spaced plates, each of annular form and arranged in parallel planes, the central plate 12 being substantially thickened as at 14 (Figure 3) in order to form a solid connection with the outer perimeter of the bell-like portion 8 of the rotor support. The relatively thick portion 14 of the plate 12 may project radially inwardly of the lateral friction plates 16 and 18 which may be disposed at opposite sides thereof for engagement in the usual manner with stator members (not shown). The friction plates 16 and 18 are relatively thick as compared with the central support plate 12, said friction plates 16 and 18 being disposed at equal distances on opposite sides of the central support plate or mounting plate 12. Integrally joining the central plate 12 with the friction plates 16 and 18 on opposite sides thereof are a series of equally spaced blades 20, 20, said blades being equally spaced around the rotor with approximately four degrees between adjacent blades as illustrated in the present embodiment. The blades joining the central plate 12 with the friction plates 16 and 18 are arranged in parallel planes so that two of the blades 20, 20 serve as a column for resisting the braking pressures applied to the braking surfaces 22 and 24 at opposite sides of the rotor. The manner in which the blades 20, 20 at opposite sides of the rotor are placed in pairs, each pair forming a column between the friction plates at opposite sides of the rotor is illustrated in the view of Figure 2, immediately above the middle thereof, where the outer extremities or edges of the blades are clearly shown aligned at opposite sides of the rotor.

While the friction plates 16 and 18 are relatively thick as compared with the central support plate 12, it is contemplated that a substantial portion of the thickness of each of the friction plates will be worn away in use and that each of said plates may be worn down to a thickness comparable to that of the central plate 12 without undue stress of the structure illustrated. It may be noted that in my novel structure the pressure applied at the friction surfaces 22 and 24 at opposite sides of the rotor is evenly distributed among the blades 20, 20 which are evenly disposed about the circumference of the rotor as already described and inasmuch as the blades 20, 20 at opposite sides of the rotor are aligned with each other thus forming a column across the rotor with each pair of blades and with the columns thus formed evenly disposed around the rotor, I am able to calculate quite accurately the stresses to which my novel rotor may be safely subjected. In this particular structure, the space between adjacent columns as indicated A (Figure 2) is subjected to bending stresses as a result of the braking pressure as applied and the portion of the friction plate represented by the space A acts as a beam under such pressure, and the stresses to which it will be subjected in a symmetrical manner such as that illustrated may be calculated with reasonable accuracy.

Each of the blades 20 is relieved at its outer edge as at 26, and the friction plates 16 and 18 as well as the central plate 12 may be smoothly finished to an identical outside diameter, while the friction plates 16 and 18 may be finished as at 28, 28 to an identical inside diameter. The inner edges of the blades 20, 20 may be arcuately

relieved as indicated at 30, 30 (Figure 3) in a manner similar to the form of the outer edges thereof. The structure of the blades at opposite sides of the rotor 10 contemplates such an arrangement as will afford equal cooling capacity for the friction surfaces at opposite sides of said rotor, inasmuch as the form and arrangement of the blades 20, 20 is similar to and performs the functions of a rotary type of blower so that when the rotor is in normal operation, rotating at a relatively high rate of speed, peripheral force acts to throw outwardly the air between the blades and thus to draw air into slots or openings 32, 32 between adjacent blades, said air being drawn into the spaces at opposite sides of the rotor in substantially equal volume inboard and outboard of the rotor support member 2.

Figure 3 illustrates the manner of mounting my novel rotor to the hub of a wheel generally designated 34 and comprising a hub 36 which may be press-fitted as at 38 on the axle 40 inboard the journal end 42. The hub 36 may be machine finished about its outer perimeter at the outboard edge in order to afford an exact concentric fit as at 44 with the bore which may be machined on the inboard face of the hub portion 4 of the rotor, said bore being defined by the annular flange 46 at the outer perimeter of said hub portion. This manner of providing an exact concentricity of the rotor with the wheel is important when it is desired to maintain a relatively small wheel hub diameter. If a larger wheel hub diameter is to be utilized with regard to the rotor structure, a manner of connection similar in principle may be utilized as illustrated in Figure 4 where the rotor hub member 48 is formed with a bore defined by a flange 50 about its inner perimeter for concentric fit as at 52 with a groove machined about the wheel hub 54 adjacent the inner perimeter thereof, at its outboard edge and relieved as at 56 from the supporting axle fragmentarily shown at 58. In the modification of Figure 4 securing stud bolts 60, 60 may be utilized to fix the rotor on the wheel hub and a similar securing means 60, 60 may be utilized in the modification illustrated in Figure 3. As illustrated in Figure 1, the rotor support member 2 has formed about its inner perimeter equally spaced lugs 62, 62 which may be drilled as at 64, 64 for reception of the before-mentioned securing bolts 60, 60. Between the lugs 62, 62 may be formed relieved areas 66, 66 thus reducing substantially the weight of the casting and at the same time affording convenient sections for modern foundry practice.

Certain details of my novel form of rotor support are best shown in Figures 6, 7, and 8 wherein it may be noted that the outer perimeter is formed with a serrated edge with equally spaced smooth wedge shaped lugs 68, 68 defined by intervening slots 70, 70, the wedge shape of said lugs and slots being such as to afford a firm grip on the metal which may be cast therearound as already described. The smooth bell-shape of the plate portion of the support member 2 is well illustrated at 6, 6 in the sectional views of Figure 7 and 8, and Figure 8 illustrates the section through the central portion of the lug 62 before drilling thereof for the securing studs. The section of Figure 7 is taken centrally through a slot 66 between adjacent lugs 62. As viewed in Figure 6, the lugs 62, 62 together with the intermediate relieved portions 72, 72 adjacent the respective slots 66, 66 define a scallop-like formation of the inner perimeter of the support mem-

ber 2. The view of Figure 6 is taken from the inboard face of the rotor support whereas the view of Figure 1 is taken from the outboard face thereof. In the view of Figure 6, the securing lugs 52, 62 are illustrated undrilled. It will be recognized that said lugs may be drilled at varied diameters to accommodate different wheel hubs.

When my novel form of rotor is applied in the manner as illustrated in Figure 3, the relatively wide space between the blade portion of the supporting wheel 34 and the adjacent friction plates 16 and 18 of the rotor affords a large air intake so that the cooling air may be drawn through the blades of the rotor at the inboard and outboard sides thereof, substantially in the manner illustrated by the curved arrows indicated at "X" and "Y" (Figure 3). Under certain conditions, however, it will be understood that it is desirable to secure greater turbulence of the air within the blower by reducing the radial depth of the central plate. When such a condition is encountered, it may be desirable to utilize a modified form of rotor such as illustrated in Figure 5 wherein the oppositely disposed friction plates 102 and 104 may be joined by equally spaced blades 106, 106, said blades thus forming substantially solid columns between said plates for equal distribution of stress incurred by pressure applied at surfaces 108 and 110 in a manner similar to that of the previous modification. In this modification however, the supporting portion of the rotor may have a ring-like member 112 of general V-section having a connection at 114 centrally of its inner perimeter to the rotor support 116 in a manner similar to that described for the previous modification, said ring 112 having a relatively shallow depth as compared with the friction plates 102 and 104. In this modification the air intake from the inboard and outboard sides of the rotor may be as illustrated by the curved arrows "M" and "N" but in this case it is contemplated that the total air intake from "M" will be somewhat less than that from "N," and it will be necessary to equalize the two in some manner to afford equal heat dissipation from the respective inboard and outboard friction plates 102 and 104. This will be accomplished in the structure illustrated in Figure 5 by the turbulence which will result in the mixture of the air from the intakes at "M" and "N," said turbulence reducing somewhat the speed of flow of the air in the spaces between adjacent blades 106, 106 and so permitting substantially equal heat dissipation from the respective friction plates.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. A composite brake rotor structure comprising a central support casting of bell-like form with wheel connecting means at one side thereof, and a serrated perimeter at the opposite side thereof, a rotor-blower element cast on said serrated perimeter, said element comprising spaced annular friction plates, and blades equiangularly arranged around the perimeter of said rotor and integrally formed with said plates, each of said blades forming a column between the opposed friction plates for resistance of pressures applied

thereto, and a central ring-like support member integrally formed with said plates and blades and having imbedded therein said serrated perimeter, said ring-like support member having a radial depth substantially equal to the radial depth of said friction plates whereby said rotor is divided into independent blower portions, one of said blower portions being operative to discharge air from one side of said rotor structure and the other of said blower portions operative to discharge air from the opposite side thereof.

2. A composite brake rotor structure comprising a support casting of bell-like form with wheel connecting means at one side thereof, and a serrated perimeter at the opposite side thereof, a rotor element cast on said serrated perimeter, said rotor element comprising spaced annular friction plates, and blades equiangularly arranged around the perimeter of said rotor and integrally formed with said plates, each of said blades forming a column between the opposed friction plates for resistance of pressures applied thereto, and a central ring-like support member integrally formed with said plates and blades and having imbedded therein said serrated perimeter, said ring-like support member having a relatively shallow radial depth as compared with said friction plates to permit maximum turbulence of the air currents received through said rotor member from opposite sides of said support casting.

3. A composite brake rotor structure comprising a central support casting of bell-like form with wheel connecting means at one side thereof, and a serrated perimeter at the opposite side thereof, a rotor element cast on said serrated perimeter, said rotor element comprising spaced annular friction plates, and blades equiangularly arranged around the perimeter of said rotor and integrally formed with said plates, each of said blades forming a column between the opposed friction plates for resistance of pressures applied thereto, and a central ring-like support member integrally formed with said plates and blades and having imbedded therein said serrated perimeter, said ring-like support member having a radial depth substantially equal to the radial depth of said friction plates whereby said rotor is divided into independent substantially equal blower portions.

4. In a combination brake rotor and blower structure, a central disc having at its small diameter end wheel connecting means and at its large diameter end an annular flange, a rotor-blower element cast on said flange and comprising spaced friction plates of annular form and an intermediate support plate, said support plate having said flange imbedded in its inner perimeter, and radial blades integrally formed with all of said plates and equiangularly spaced about the circumference of said element, said blades at opposite sides of said element lying in co-planar pairs with the blades of each pair forming a continuous column from one friction plate to the other through said support plate.

5. In a brake rotor, a bell-like support casting having a hub portion with a bore defined by an annular flange forming a means of concentric connection to a supporting wheel, said casting having a serrated outer perimeter affording support for an associated rotor member, said rotor member comprising spaced annular friction plates and an intermediate support plate with radially arranged blades joining said support plate with the respective friction plates to define blower

means at opposite sides of said rotor, said support plate being cast on said serrated perimeter, said blades being arranged in pairs at opposite sides of said rotor, each of said pairs defining a column extending between said friction plates.

6. A composite brake rotor structure comprising a central casting of bell-like form with wheel connecting means at one side thereof, and a serrated perimeter at the opposite side thereof, a rotor element cast on said serrated perimeter, said rotor element comprising spaced annular friction plates, and blades equiangularly arranged around the perimeter of said rotor and integrally formed with said plates, each of said blades forming a column between the opposed friction plates for resistance of pressures applied thereto, and a central ring-like support member integrally formed with said plates and blades and having imbedded therein said serrated perimeter.

7. In a combination brake rotor and blower structure, a bell-like support member having at its small diameter end wheel connecting means and at its large diameter end a serrate perimeter, a rotor-blower element cast on said support member, said element comprising a plurality of annular friction plates and an intermediate relatively thin support plate cast on said serrate perimeter, radially disposed blades integrally formed with said plates and equiangularly arranged around the circumference of said element, said blades being arranged in pairs at opposite sides of said element, each of said pairs forming a continuous column from one of said friction plates to the other thereof.

8. In a combination brake rotor and blower structure, a central disc of bell-like form having at its small diameter end wheel connecting means and at its large diameter end a serrate flange, a rotor-blower element cast on said flange and comprising spaced friction plates of annular form and an intermediate support plate, said support plate having said flange imbedded in its inner perimeter, and radial blades integrally formed with all of said plates and equiangularly spaced about the circumference of said element, said intermediate plate having a radial depth substantially equal to that of said friction plates thus dividing said element into blower portions at opposite sides thereof for circulating a cooling medium for dissipation of heat from said respective friction plates.

9. In a brake rotor, a bell-like support casting having a hub portion with a bore defined by

an annular flange forming a means of concentric connection to a supporting wheel, said casting having a serrated outer perimeter affording support for an associated rotor member, said rotor member comprising spaced annular friction plates and an intermediate support plate with radially arranged blades joining said support plate with the respective friction plates to define blower means at opposite sides of said rotor, said support plate being connected to said serrated perimeter.

10. In a brake rotor, a central support having a hub arranged for concentric connection to a supporting wheel, a combination friction rotor and blower casting comprising a pair of annular friction plates with a centrally located supporting plate and a plurality of radially arranged blades defining columns between said plates, said rotor and blower casting being cast about the outer perimeter of said support with the support imbedded in the central supporting plate.

11. In a brake rotor, at least three substantially parallel annular plate members, blade means extending between said members, and support means for said rotor connected to an intermediate member, all of said members being of substantially the same inner and outer diameters.

12. In a brake rotor, at least three substantially parallel plate members, an opening in an outer plate member, blade means extending between said members, and support means for said rotor extending through said opening and joining an intermediate member, all of said members being of substantially the same outer diameter.

13. In a brake rotor, three substantially parallel annular plates, blade means extending therebetween, a hub member joining the intermediate plate, the other plates having outer diameters substantially as great as that of said intermediate plate and presenting friction surfaces on their remote surfaces.

14. In a brake rotor, three substantially parallel annular plates, blade means extending therebetween, a hub member joining the intermediate plate, the other plates having outer diameters substantially as great as that of said intermediate plate and presenting friction surfaces on their remote surfaces, the thickness of said other plates being at least equal to that of said intermediate plate.

CARL E. TACK.
